UNITED STATES PATENT OFFICE.

DANIEL EARL SHOWALTER, OF FRANKFORT, KENTUCKY.

REMINDER.

Application filed January 9, 1926. Serial No. 80,263.

My invention relates to improvements in devices commonly known as reminders and adapted particularly for household use to indicate the condition of stocks or supplies of various household commodities so that the person who has charge of the purchasing of such commodities will have a reminder when he glances at the device that the supplies of certain commodities require replenishing.

The invention consists in the combinations, constructions and arrangements herein described and claimed.

An object of the invention is the provision of an indicating device of the character described which is simple in construction and at the same time includes indicating means adapted to be adjusted with relatively great ease to indicate that a relatively great number of acts or any one of such acts should be performed.

Other objects and advantages of the invention will be apparent from the following description, considered in conjunction with the accompanying drawings, in which

Figure 1 is a face view of an indicating device embodying the invention, and

Figure 2 is an edge view of the device.

The improved indicating device comprises a supporting member or body 1 which is shown as being a plate of light gauge and made of any suitable material, such as cardboard, fiber, metal or the like. The plate 1 preferably is formed with a raised relatively narrow marginal portion or bead 2 on its front face, the outer edge of this bead preferably being beveled so as to produce a marginal flange 3 which tapers in thickness towards its outer edge. Also, the plate 1 preferably is rectangular in configuration.

The plate 1 has a longitudinally extending or vertical guide slot 4 produced therein to extend substantially along the longitudinal axial line of the plate 1 for nearly the full length of the plate 1. The slot 4 is merged at its upper end into a transverse opening 5 which is of greater area than the width of the slot 4 and is adapted for the reception of a cylindrical eyelet or sleeve 6. The eyelet or sleeve 6 has a flange 7 at its front end for limiting the axial movement of the sleeve 6 in the opening 5 in a rearward direction and the sleeve 6 preferably has a relatively tight fit with the wall of the opening 5 so that it normally will remain in

position in the opening 5 but can be displaced from the opening 5 in a forward direction when desired for a purpose to be presently stated.

The slot 4 is formed at intervals for part 60 of its length with a plurality of pairs of oppositely extending lateral branches 8, each of which is relatively short and is approximately as wide as the slot 4 except that the outer end of the branch is widened 65 slightly by providing an arcuately curved notch or seat 9 in the bottom wall of the branch. The uppermost pair of branches 8 preferably is located adjacent to the junction of the slot 4 with the opening 5 and the lowermost pair of branches is located at a considerable distance above the lower end of the slot 4.

The invention contemplates the provision of a plurality of markers or indicating elements, each of which is freely movable along slots 4 to and from position to rest in the seat 9 at the outer end of any one of the branches 8 of the slot. These markers or indicating elements are shown as being buttons, each of which has a shank 10 of greater length than the thickness of the slotted portion of the plate 1 and heads 11 at opposite ends of the shank 10, the heads 11 being of greater diameter than the width of the slot 4 but of slightly less diameter than the opening 5.

From the foregoing description of the various parts of the device, the operation thereof may be readily understood. The provision of the vertical slot 4 and the branches 8 substantially intermediate the side edges of the plate 1 assures adequate space at each of the opposite sides of the series of pairs of branches 8 for the production of suitable indicia on the face of the plate in association with the adjacent branches 8 of the guide slot. For example, each branch 8 of the guide slot may be identified by the name of a particular article or household commodity which is produced on the face of the plate 1 substantially in line with that particular branch 8 of the slot and of course at the outer end of said branch 8. The markers are moved through the opening 5 into the guide slot 4, the sleeve 6 having first been removed from the opening 5. The shanks of the markers will slide freely in the guide slot 110 and these markers may be disposed in super-

posed relation in the lower end portion of the guide slot below the lowermost branches 8. After the markers have been placed in the guide slot 4, the cylindrical member 6 is again placed in the opening 5 and serves as a stop for preventing displacement of any one of the markers from the slot 4 at the upper end of said slot.

In use, a marker is moved upwardly along 10 the guide slot 4 and into the branch 8 which indicates a particular article or commodity which is to be purchased. It is obvious that the names of various acts which require performance may be produced on the face of 15 the plate 1 in association with the branches 8 instead of names of household commodities or articles of food. The shanks of the markers will rest in the seats 9 when the markers are at the outer ends of the 20 branches 8 of the slot and are not likely to be dislodged accidentally from positions at the outer ends of the branches 8 when the plate 1 is tilted slightly in any direction or is vibrated.

25 The portions of the face of the plate 1 at opposite sides of the lower end portion of the slot 4 may have any suitable designs, indicia, advertising matter or the like produced thereon, such as the ornamental 30 signs indicated at 12 in Figure 1. The tubular member 6 in the opening 5 may accommodate a nail or like supporting element, not shown, for the support of the device.

Obviously, the invention is susceptible of 35 embodiment in forms other than that which is illustrated in the accompanying drawings and which has been described in the foregoing specification, and I therefore consider as my own all such modifications and adaptations thereof as fairly fall within the 40 scope of the appended claims.

I claim:—

1. An indicating device of the character described comprising a body of light gauge 45 material having a vertical slot formed therein, said slot having a plurality of vertically spaced lateral branches, and a marker movable along the slot to and from position to enter any one of said lateral branches, 50 said body having indicia produced thereon adjacent to each branch.

2. An indicating device of the character described comprising a plate having a vertical slot formed therein extending longitudinally of the plate, said slot having pairs of laterally extending branches and being merged at its upper end into a transverse opening through the plate, and a marker movable through said transverse opening 60 to and from position to enter and slidably engage with said slot, said marker being movable along the slot into and from any one of said branches.

3. An indicating device of the character 65 described comprising a plate having a vertical

slot formed therein extending longitudinally of the plate, said slot having pairs of laterally extending branches and being merged at its upper end into a transverse opening through the plate, and a marker 70 movable through said transverse opening to and from position to enter and slidably engage with said slot, said marker being movable along the slot into and from any one of said branches, the lowermost of said pairs of branches being located a considerable distance above the lower end of said slot, said plate having indicia produced on the face thereof in association with said branches of 75 said slot.

4. An indicating device of the character described comprising a plate having a vertical slot extending substantially along the longitudinal axial line of the plate, said slot being merged at its upper end into a transverse opening through the plate, said slot having pairs of oppositely extending lateral branches, and markers adapted to be moved through said transverse opening to and from said slot and being movable along the slot and into and from said branches, each of said markers comprising a shank adapted to slide in said slot, and heads at opposite ends of said shank and each of greater diameter than the width of said slot, at least one of said heads being of less diameter than said transverse opening in the plate, and a stop member adapted to be removably disposed in said transverse opening to prevent return movement of said markers from said slot into said transverse opening, said stop member comprising a tubular body fitting in the transverse opening and having a flange at its front end of greater diameter 95 than said transverse opening.

5. An indicating device of the character described comprising a plate having a vertical slot extending substantially along the longitudinal axial line of the plate, said slot being merged at its upper end into a transverse opening through the plate, said slot having pairs of oppositely extending lateral branches, and markers adapted to be moved through said transverse opening 100 to and from said slot and being movable along the slot and into and from said branches, each of said markers comprising a shank adapted to slide in said slot, and heads at opposite ends of said shank and each of greater diameter than the width of said slot, at least one of said heads being of less diameter than said transverse opening in the plate, and a stop member adapted to be removably disposed in said transverse opening 105 to prevent return movement of said marker from said slot into said transverse opening, said stop member comprising a tubular body fitting in the transverse opening and having a flange at its front end of greater diameter 110 than said transverse opening.

- ing, said tubular stop member being adapted to slip over a nail or like elongated supporting member, whereby said plate may be suspended from said supporting member.
- 5 6. An indicating device of the character described comprising a plate having a vertical slot formed therein, said slot having pairs of lateral branches, said plate having a marginal bead on its outer face and having a flange at its marginal edge, the lower-
- most of said pairs of branches being located at a considerable distance above the lower end of said slot, indicia on the face of said plate in association with said branches and markers movable along said slot to and from said lateral branches, the surface of the face of said plate at opposite sides of the lower end portion of said slot being adapted to have other indicia produced thereon.

DANIEL EARL SHOWALTER.
